UNITED STATES PATENT OFFICE.

EDWARD F. WALZ, OF MINNEAPOLIS, MINNESOTA, ASSIGNOR TO ENGRAVOGRAPHIA,
OF NEW YORK, N. Y., AN ASSOCIATION.

DESIGN FOR A BADGE OR SIMILAR ARTICLE OF MANUFACTURE.

Application filed August 19, 1925. Serial No. 14,517. Term of patent 14 years.

To all whom it may concern:

Be it known that I, EDWARD F. WALZ, a citizen of the United States, residing at Minneapolis, in the county of Hennepin and State of Minnesota, have invented a new, original, and ornamental Design for a Badge or Similar Article of Manufacture, of which the following is a specification, reference being had to the accompanying drawing, forming a part hereof.

Figure 1 is a plan view of a badge or

similar article of manufacture, showing my new design.

Figure 2 is a sectional view of a badge or similar article of manufacture showing my new design.

I claim:

The ornamental design for a badge or similar article of manufacture, as shown.

July 28th 1925.

EDWARD F. WALZ.
